UNITED STATES PATENT OFFICE.

JOSIUA POOL AND JOSEPH POOL, OF GREENSBURG, INDIANA.

DESIGN FOR MONUMENTS.

Specification forming part of Design No. **11,468**, dated October 21, 1879; application filed September 27, 1879.
[Term of patent 7 years.]

To all whom it may concern:

Be it known that we, JOSHUA POOL and JOSEPH POOL, of Greensburg, in the county of Decatur and State of Indiana, have originated and designed a New Monument, of which the following is a full, clear, and exact description, reference being had to the accompanying drawing, making part of this specification.

The nature of our design is fully represented in the accompanying drawing; and it consists of a monument having a square base, A, made in one or more pieces, on which is mounted a second base, B, which is square and finished at its top with four gables having round tops B' and a square center, B², tapered to fit the lower end of the die C.

The square die C is provided on all sides with a raised or sunk panel, C'.

The cap D is square at its base, with a molding to match the top of the die C, and its top furnished with round-topped gables D' on its four sides, with a square tapering center, D², finished at its top to fit the base of the spire E.

The spire E is square, and has a projecting gable, F, on every side at its base, which is round-topped. The spire has near its top a raised ornament, F', consisting of a round-topped gable on all four sides and a drop on each corner of the spire, as shown in the accompanying drawing.

What we claim as new, and desire to secure by Letters Patent, is—

1. The design of a sectional monument, as shown, consisting of a square base, A, the second base, B, with round-topped gables B', and square die C, having either raised or sunk panels C', above which in its turn is fitted the square cap D, having round-topped gables D' on its four sides, and square tapering center D², fitted to the base of the square spire E, said spire being finished at the base with a raised round-topped gable, F, on all four sides, consisting of round-topped gables and a drop on each corner of the spire, as shown in the drawing.

2. The design of a sectional monument as a whole, with its various sections fitted together, the base B, the die C, the cap D, and the spire E, each, except the die C, being provided with round-topped gables, as shown and described.

3. The base B, the cap D, and the spire E, and each part of each section constructed and arranged as shown.

In testimony whereof we have signed our names to this specification in the presence of two subscribing witnesses.

JOSHUA POOL.
JOSEPH POOL.
